UNITED STATES PATENT OFFICE.

WILLIAM D. COOLIDGE, OF SCHENECTADY, NEW YORK, ASSIGNOR TO GENERAL ELECTRIC COMPANY, A CORPORATION OF NEW YORK.

X-RAY TUBE.

1,355,126.

Specification of Letters Patent. Patented Oct. 12, 1920.

Application filed December 16, 1916. Serial No. 137,355.

To all whom it may concern:

Be it known that I, WILLIAM D. COOLIDGE, a citizen of the United States, residing at Schenectady, in the county of Schenectady, 5 State of New York, have invented certain new and useful Improvements in X-Ray Tubes, of which the following is a specification.

The present invention comprises a new 10 X-ray device and its object is to cut off or screen undesired X-rays coming from the parts of the target or anode other than the focal spot. With this object in view I have provided a screen or shield consisting of 15 material such, for example, as a heavy metal which is substantially impervious to X-rays and which is negatively charged with respect to the anode during the operation of the device.

20 The novel features and benefits of my invention will be explained in connection with the accompanying drawings in which Figure 1 shows in outline an X-ray tube provided with a shield which is connected to the cathode; Fig. 2 is a detail sectional view 25 of the cathode and focusing member; Fig. 3 is a detail perspective view of a shield supported at the anode end of the tube and electrically insulated from both electrodes; 30 Fig. 4 illustrates a shield used in conjunction with an anode hood, and Fig. 5 is a detail view of a special form of screen.

It has been suggested heretofore to place 35 a screen composed of material transparent to X-rays about the anode of an X-ray tube which is dependent for its operation on the ionization of residual gas within the tube. The expressed object of this construction was to avoid the action of secondary rays.

40 In a tube operating by the ionization of gas, there are present positive ions as well as negative electrons. An anode screen transparent to X-rays in this type of tube, even though insulated from the anode, will be 45 continuously bombarded by negative electrons as any negative charge which tends to accumulate on the screen will be neutralized by the positive ions. The screen itself, therefore, is a source of X-rays.

50 However, in a tube operating independently of gas ionization, the positive ions are negligible and a screen insulated electrically from the anode accumulates a negative charge which prevents further bombard-

ment by electrons, and the shield hence does 55 not become itself a source of X-rays.

Referring to Fig. 1, the X-ray device here shown comprises a tube in which are sealed a cathode 2 and an anode 3. The cathode, as shown in greater detail in Fig. 2, comprises a coiled filament of refractory metal, for example, tungsten, connected to conductors 4, 5, sealed into a stem 6. Surrounding the cathode proper is a metal tube 7, concave or dished in part, which focuses the 65 discharge from the cathode. This focusing tube 7 is supported by a conductor 8 attached to a split tube 9 sprung over the stem 6, and is electrically connected to the 70 cathode.

The anode or target 3 consists of tungsten or other suitable material, and is carried by a stem 10 supported by a tube 11 consisting of iron and held in place by friction within the tubular extension of the envelop. 75 A sealed-in conductor 12 makes electrical connection to the anode. The cathode is heated by a battery 13 in circuit with which is a switch 14.

The described device is evacuated to a 80 pressure so low that positive gas ionization is substantially absent during its operation, as described in my Patent No. 1,203,495, issued October 31, 1916.

When a sufficiently high potential is impressed on the electrodes, as indicated by the connection of the cathode and the anode to terminals of the secondary of a transformer 85 15, by the conductors 16, 17, the cathode being heated to incandescence, a discharge of 90 electrons is conducted through the evacuated space and is focused upon the face of the anode to strike within a limited area known as the focal spot. By the impact of the cathode rays or electrons upon the anode 95 surface X-rays are generated. Secondary cathode rays are also generated at the focal spot and travel outwardly from this point and are bent back upon the anode itself by the electrostatic repulsion of the cathode 100 and the negatively charged tube walls.

These secondary cathode rays give rise to the emission of X-rays over the entire surface of the target, but, of course, with lesser intensity than at the focal spot. As a result 105 there is some loss of definition in X-ray pictures of subjects giving intense contrasts. In order to prevent these undesired second-

ary X-rays from reaching the object which is being examined, I have provided a blade-shaped screen 18 having a window 19 and consisting of a sufficient thickness of a material relatively impervious to X-rays, as, for example, tungsten or molybdenum. The screen is located within the tube between the anode surface emitting secondary X-rays and the object to be photographed or examined. The screen not only is opaque to undesired X-rays but when given the form illustrated, which does not extend entirely about the anode, it also acts by electrostatic repulsion to deflect cathode rays away from the side of the target facing the object to be examined.

As shown in Fig. 1 the screen may be mechanically connected and in electrical contact with the cathode, or the screen may be supported as shown in Fig. 3 by being attached to circular strips 20 which are sprung against the walls of the anode extension of the envelop. If desired for any particular purpose the extension of the screen about the anode may be increased.

In either of the described constructions the screen, or deflector, 18 is negatively charged during operation. In the construction shown in Fig. 1 the screen is in direct electrical contact with the cathode and therefore operates at cathode potential, and in the construction shown in Fig. 3 the screen is charged to cathode potential by the electrons emitted from the cathode or the focal spot on the anode. As the space within the tube is substantially free from positive ions the screen remains negatively charged and, therefore, is not subject to continued bombardment by cathode rays and consequently emits no X-rays. A useful beam or cone of X-rays emitted from the focal spot passes through the window 19 upon the object to be photographed or examined, while the stray rays emitted by the surface of the anode outside the focal spot are cut off, thereby giving sharp delineation.

In the construction shown in Fig. 4 the target or anode 3, is provided with a hood 21 consisting, for example, of molybdenum or tungsten. As described in my Patent No. 1,211,092, of January 2, 1917, one of the main functions of the hood is to suppress the escape of electrons emitted from the focal spot to the outer surface of the anode. The presence of the negatively charged member 18, still further reduces the escape of electrons through the window 22 by electrostatic repulsion. Instead of escaping from the window and then impinging on the outer surface of the anode the electrons are

largely deflected and strike either the inner surface hood 21 or the anode itself where the X-rays generated by the impact cannot affect the operation of the tube and the sharpness of definition. In some cases the window 19 may be barred by a grid consisting of fine wires 23 which increase the electrostatic repulsive effect. The small diameter and nearness of these wires to the source of X-rays prevents the casting of appreciable shadows. Such electrons as do escape and strike the outer surface of the target produce no appreciable effect as they are cut off by the screen 18 which is opaque to X-rays.

What I claim as new and desire to secure by Letters Patent of the United States, is:—

1. An X-ray tube comprising the combination of a refractory cathode, means for heating the same to incandescence, a co-operating anode, an inclosing sealed envelop, the space within said envelop and the metal parts therein being evacuated to a pressure so low that conduction therein occurs substantially independent of positive ionization, and a shield substantially impervious to X-rays located to intercept X-rays from parts of the anode other than the face of the anode on which the cathode rays are focused, said shield being electrically connected to said cathode.

2. In an X-ray tube operating by substantially pure electron conduction independently of positive gas ionization, the combination of an inclosing envelop, a cathode, an anode, a hood for said anode having windows respectively for the entrance of cathode rays and the escape of X-rays and a member acting as deflector and screen charged negatively with respect to the anode located adjacent the window through which X-rays escape, said member being provided with a window to permit the passage of desired X-rays.

3. In an X-ray tube operating by substantially pure electron conduction without appreciable positive gas ionization and having a hood provided with a window for the escape of X-rays upon the charge receiving face of the anode, a screen adjacent the anode charged negatively with respect to the anode during operation of the device and having a window registering with the window in the hood through which X-rays escape, said screen being connected to the cathode and a grid of wires for the window of said screen.

In witness whereof I have hereunto set my hand this 14th day of December, 1916.

WILLIAM D. COOLIDGE.
